CLAIM

The ornamental design for a phone conversation tapping device for interconnection between a telephone and a recorder, as shown and described.

DESCRIPTION

FIG. 1 shows a rear perspective view of the present invention;

FIG. 2 shows a front perspective view of the present invention;

FIG. 3 shows a side view of the present invention;

FIG. 4 shows the other side view of the present invention;

FIG. 5 shows a top view of the present invention; and, FIG. 6 shows a bottom view of the present invention.

FIG. 1

FIG. 2

FIG. 3

FIG. 4

FIG. 5

FIG. 6
